UNITED STATES PATENT OFFICE.

MATHIAS J. KASPAKI, OF CHICAGO, ILLINOIS, ASSIGNOR, BY MESNE ASSIGNMENTS, TO INTERNATIONAL HARVESTER COMPANY, A CORPORATION OF NEW JERSEY.

CONTROLLING MECHANISM FOR BALLING MACHINES.

Application filed February 5, 1918. Serial No. 215,495.

To all whom it may concern:

Be it known that I, MATHIAS J. KASPAKI, a citizen of the United States, residing at Chicago, in the county of Cook and State 5 of Illinois, have invented certain new and useful Improvements in Controlling Mechanism for Balling Machines, of which the following is a full, clear, and exact specification.

10 This invention relates to balling machines and more particularly to controlling mechanism for balling machines and to the tension devices employed in connection with said machines.

15 The object of the invention is to provide means for automatically and manually controlling the operation of machines of the class described, and to provide means for so tensioning the guiding and polishing member that a uniform and adequate degree of 20 tension will be obtained at all times.

With the above objects in view the invention consists, briefly, in a twine guiding member, actuating means for the guiding member and a plurality of controlling means for the actuating means, comprising manually and automatically operable controlling means, the manually operable means being operable from the front or from the rear of 25 the machine and the automatically operable controlling means being thrown into operation when the passage of the thread or twine through the machine is interrupted.

The twine guiding and polishing member 30 is provided with tensioning mechanism such as gravity actuated means for holding the device against the ball being wound, and additional means, such as a friction brake, is provided to assist the tensioning mechanism 35 in maintaining a uniform and constant tension and to prevent sudden release or snapping back of the tensioning mechanism.

40 I have illustrated one embodiment of my invention in the accompanying drawings, and in these drawings,—

Figure 1 is a front view in elevation showing my improved balling machine;

Fig. 2 is a side elevation looking toward the right in Fig. 1;

50 Fig. 3 is a side elevation looking toward the left in Fig. 1;

Figs. 4, 5 and 6 are enlarged details illustrating the mechanism for shifting the belt and stopping the machine;

55 Figs. 7 to 13 inclusive are detail views on

an enlarged scale illustrating the construction of the automatic stopping mechanism which controls the operation of the machine when the thread breaks or when the ball is completed;

Fig. 14 is a front elevation on an enlarged scale of the twine guiding and ball polishing mechanism, and

Fig. 15 is a sectional view illustrating the reciprocatory feeding mechanism for the twine guiding member.

The frame 20 of the machine is of the usual construction having a front upright portion 21 and a horizontal rear portion 22. The portion 22 supports an upright supporting standard 23 which in turn carries a supply reel 24 and the associated parts. The supply reel 24 comprises radial arms 25 carried by a sleeve which in turn is rotatably carried on a shaft 26 mounted in bearings on the standard 23. The sleeve which carries the radiating reel arms has secured thereto at one end a notched disk 27 which cooperates with a lever 28 in such a manner that a pin 29 carried by the lever is adapted to rest in one of the notches of the disk and thereby secure the reel against rotation.

The tensioning device for the supply bobbins comprises a plurality of V-shaped plates 30 pivoted to an arm 31 which in turn is secured to a sleeve 32 journaled on a shaft carried by the standard 23. This sleeve 32 carries at one end a triangular plate 33 provided on one of its sides with a flat bearing portion or track 34, and the sleeve 32 has secured at its opposite end a grooved disk 35. A chain 36 is secured to the disk 35 and is connected at its opposite end to a vertical link 37 which in turn is connected at its lower end by a pin and slot connection with a lever 38 pivoted at 39 to the frame of the machine. The lever 38 is connected at its opposite end by a pin and slot connection with a foot lever 40, and by pressing on the front end of this foot lever the operator

when starting the machine can rotate the disk 35, sleeve 32, arm 31, and thereby lift the tension devices 30 from contact with the supply bobbin.

The track 34 on the plate 33 carries a pin 41 secured against displacement by means of suitable flanges, and this pin 41 is secured to a downwardly extending rod 42 which carries at its lower end a weight 43. If desired, the pin 41 may be

provided with an anti-friction roller to facilitate the shifting of the belt.

2
cilitate its sliding movement on track 34. The weight rests on a spring 44 which is secured against removal by means of a nut 45. The weight 43 acting through the rod 42, pin 41, track 34 and plate 33, increases the tension on the ball as illustrated in Fig. 3.

The tensioning device above described is that of the patent to G. L. Rue, No. 1,385,925, 10 July 26, 1921 and forms no part of my invention and has been shown merely incidentally, and it should be understood that any other suitable form of tensioning mechanism may be employed in this machine.

15 The balling machine proper comprises automatic stop mechanism which is actuated when the thread breaks or when the supply bobbin runs out, manually operable stop mechanism which may be actuated from 20 either the front or rear of the machine, and twine guiding and ball polishing mechanism, and the driving means therefor. Means are also provided for securing the proper tension on the twine guiding and ball polishing 25 mechanism.

The automatic stop mechanism will first be described. After the twine or yarn 46 leaves the supply bobbin, it is carried around a rotatably mounted V-shaped sheave 47, to 30 a carriage 48 slidably mounted on bars 49 carried by the frame of the machine. This carriage 48 is provided with a sheave 50 and is normally pressed toward the rear of the machine by springs 51 carried by the bars 35 49. Buffer springs 49' are provided on the rear portions of rods 49 to cushion the carriage when the twine breaks and the carriage is pressed rearwardly by springs 51. From 40 an inspection of Fig. 3 it will be seen that the tension on the thread as it is being drawn from the supply bobbin and over the sheaves 47 and 50, normally pulls the carriage 48 toward the front of the machine and against the tension of the springs 51, but when the 45 thread or twine is broken or releases the springs 51 press the carriage rearwardly on the bars 49 and by means of suitable trip controlled mechanism hereinafter described, stop the machine. This cooperating mechanism will now be described.

The carriage 48 is provided on its upper rear portion with a projection 52, which is located in the path of, and is adapted to contact with, the lower end 53 of a lever pivoted 55 at 54 to the frame of the machine. The opposite end of this lever has a forwardly projecting substantially horizontal bearing portion 55 which normally contacts with a notched member 56 secured to a pintle 57 journaled on the machine frame. This member 56 is elongated and its inner portion forms a stop for a member 58 pivoted to the frame at 59 and bifurcated at its upper end as shown at 60. The upper bifurcated end 60 of the member 58 receives a downwardly

projecting rib 61 carried by a lever 62 which carries at its inner end a sleeve 63 pivoted on a vertical pivot 64 to the machine frame. Formed integrally with the sleeve 63 is an arm 65 which carries at its opposite end a link 66 pivoted at 67 to a sleeve 68 which in turn carries a bifurcated belt shipping fork 69. The sleeve 68 is slidably mounted on a rod 70 and is normally pressed by a spring 71 in a direction to ship the belt 72 from the fast to the loose pulley. The operation of this automatic stop mechanism will now be briefly described.

When the thread or twine breaks, the springs 51 press the carriage 48 rearwardly on the rods 49, and the upwardly projecting portion 52 of the carriage contacts with the downwardly projecting portion 53 of a lever, the upper end 55 of which is thereby pressed downwardly, moving the member 56 on its pivot. When this member 56 is forced downwardly the pivoted member 58 is free to rotate about its pivot in a clockwise direction, thereby releasing lever 62 and with it the sleeve 68 and belt shipping fork 69 which are forced by the action of the spring 71 toward the left in Fig. 1, thereby shipping the belt from the fast to the loose pulley.

The means for shifting this mechanism automatically when the bobbin being wound is full, and for manually shifting the belt shipper from either the front or the back of the machine, will next be described.

The pintle 57 has fixed to it at its front end a substantially vertically disposed lever 73 having at its lower end an adjustable screw 74. The lever 73 is normally forced in a clockwise direction about its pivot by means of a contractible spring 75, one end of which is connected to the lower part of the lever and the other end of which is connected to the frame. The screw 74 carried by the lower end of the lever 73 is located in the path of the twine guiding and ball polishing device 76, pivoted at 77 to the frame of the machine. After this device 76 has been forced outwardly a certain distance, by reason of its contact with the twine on the ball being wound, it will contact with the screw 74 thereby rotating the lever 73, and the pintle 57 and the member 56 carried by the opposite end of said pintle. The movement of this pivoted member 56 will have the same effect as was described above and will release the pivoted member 58, thereby allowing the clutch shipping fork, under the force of the spring 71, to ship the belt from the fast to the loose pulley. By means of the screw 74 on the lower end of the lever 73, the operator can control the size of the ball being wound.

The upwardly projecting end of the lever 73 extends in the path of a cone 78 carried by the front end of a rod 79 which in turn is provided at its rear end with a handle 80.

This rod 79 is slidably mounted in bearings 81 and 81' carried respectively on the frame of the machine and on lever 62, and said rod carries intermediate the front bearing 81' and the conical end, a spring 82 which normally presses the rod toward the front of the machine. If the operator at the rear of the machine pulls on the handle 80, the rod 79 will be pulled rearwardly and the 10 conical end 78 will contact with the upper end of the lever 73, thereby rotating that lever in an anti-clockwise direction, and also rotating the pintle 57 fixed to the lever and the member 56 fixed to the pintle. Thus 15 the belt shipping operation is actuated in the manner above described in connection with the automatic stop and the machine is stopped.

Should the operator be at the front of 20 the machine, the same result is obtained by pushing on the cone-shaped end 78 of rod 79. To put the machine into operation, the hand lever 62 is swung forwardly until the member 56 swings up into the path of the 25 lower end of member 58 which has moved backwardly as lever 62 was being moved forwardly, the upward movement of member 56 locking lever 62 and the belt shipping mechanism connected to it in active position.

30 The tensioning means for the twine guiding and ball polishing device will next be described.

As stated above, this guiding device 76 is pivoted at 77 to the frame of the machine 35 and comprises a lever, the lower end of which carries a quadrant 83 which meshes with a pinion 84 carried by a pintle 85. This pintle 85 also carries a disk 86 around the periphery of which is mounted a band 40 87 secured at one end 88 to the machine frame and secured at its opposite end at 89 to a lever 90 pivoted at 91 to the frame of the machine. This lever 90 carries on its outer end a weight 92 which exerts a downward force on the band 87, thereby putting a tension on the pinion 84 and through the pinion and quadrant 83 on the twine guiding and polishing device 76. There is also secured to the lower end of this device 76, 45 adjacent the quadrant, a link 93 pivoted at its opposite end at 94 to a bell crank lever 95 pivoted on the frame of the machine. The bell crank lever is pivoted at its opposite end to a link 96 to which is secured a weight 97.

From the above description it will be seen that the weight 97 tends to rotate the upper end of the device 76 in an anti-clockwise direction or against the surface of the ball, and that the weight 92, acting through the band 87, pinion 84 and quadrant 83, cushions or puts a brake on the tensioning mechanism and tends to make this tension uniform and to prevent any sudden change in

tension. This uniformity of tension is necessary in this type of machine since any departure from a constant tension will immediately affect the winding of the ball, produce irregularities and often a breakage of the twine. The brake band 87 and weight 92 also resists the outward movement of the guiding device 76, thereby assisting in compacting the ball and permitting the use of a smaller weight 97 than would be otherwise required. When the full ball is doffed 75 the brake band 87 prevents weight 97 from immediately throwing the guiding device 76 against the collapsible spindle, and in this way prevents a possible injury to the fingers of the operator and to the guiding 80 device. The tension device 76 is carried by a bar 98 (see Fig. 15), which is reciprocated by means of a cam 99 driven by suitable gearing 100, which, in turn, is driven in a manner hereinafter described. In Fig. 85 15 is shown also the drive for the collapsible spindle 101 mounted on the front end of a shaft 102. This shaft carries a worm gear 103 which is driven by a worm 104 carried by a shaft 105 upon which are mounted the 90 driving pulley and loose pulley which are driven by the belt 72 above described. In Fig. 2 I have illustrated the usual lever mechanism for collapsing the spindle when the ball has been wound, and it is desired 95 to take off the full ball. This mechanism comprises a foot treadle 105', pivoted to the machine frame and carrying an upwardly projecting link 106 which is pivoted at its upper end to a bell crank lever 107. This 100 lever is connected at its opposite end by a pin and slot connection to a slidably mounted rod 108 which carries at its front end a fork which projects between the flanges on a collar 109 and reciprocates this collar, 105 thereby collapsing the spindle 101 in a manner well known in the art, and not specifically herein illustrated.

The operation of the various parts of this machine has been described in connection 110 with the description of the structure and no further description of the operation is therefore thought to be necessary.

From the above description it will be seen that I have provided a simple, practical and efficient balling machine having means for automatically stopping the machine when the thread breaks, for manually stopping the machine when desired from a position in the front of or in the rear of the machine, and for tensioning the twine guiding and polishing device in such a manner that said device will not snap back and injure the hand of the operator when the full ball is doffed.

While I have in the above specification described one embodiment which my invention may assume, it should be understood that the same is capable of various modifications

and that such modifications may be employed without departing from the spirit and scope of the invention as expressed by the following claims:

5. 1. The combination with a balling machine including a spindle, a twine guiding member, and actuating means therefor; of a spring pressed slideable member adapted to be engaged by the twine and normally placing the twine under tension and a throw-out device for the actuating means including an element in the backward path of said slideable member and positioned to be engaged thereby when the twine releases said slideable member.
10. 2. The combination with a balling machine including a spindle, a twine guiding member, and actuating means therefor; of means for controlling the actuating means including a hand lever pivoted at the front of the machine and adapted to put the machine in operation when swung in one direction, trip controlled means for automatically swinging said hand lever in the other direction to stop the machine, and a secondary control element comprising a longitudinally slideable rod extending rearwardly at substantially right angles to the lever and provided with a handle at its rear end and with means at its other end for releasing said trip controlled mechanism when said rod is moved in one direction.
15. 3. The combination with a balling machine including a spindle, a twine guiding member, and actuating means therefor, of means for controlling said actuating means including a pivoted member, a carriage reciprocably mounted on the frame of the machine and having a twine guiding member thereon, means for normally forcing said carriage in one direction, and means located in the path of the carriage and normally out of engagement therewith for controlling the position of said pivoted member.

4. In a balling machine, a pivoted twine guiding member, means for constantly urging said member in one direction about its pivot, and means for cushioning the movement of said member about its pivot in either direction. 45

5. In a balling machine, a pivoted guide carrying member, means for constantly urging said member in one direction, a reciprocating element carried at one side of the pivot of said member for guiding the twine, and means operatively connected to said member at the other side of its pivot for resisting the movement of said member about its pivot. 55

6. In a balling machine, a pivoted guide carrying member, means for constantly urging said member in one direction, a reciprocating twine guide on said member and means for cushioning the movement of said member including a brake for resisting the movement of said twine guiding member about its pivot. 60

7. In a balling machine, a pivoted guide carrying member, twine guiding means reciprocably mounted on said member at one side of its pivot, a sector carried by said member at the other side of its pivot, a pinion meshing with said sector and journaled on the balling machine frame, a disk rotatable with said pinion, and friction means cooperating with said disk to retard its rotation. 70

8. In a balling machine, a pivoted guide carrying member, twine guiding means reciprocably mounted on said member at one side of its pivot, means including a band brake for resisting the movement of said member about its pivot, and a weight connected to said member and tending to swing it about its pivot in one direction. 80

In testimony whereof I affix my signature.

MATHIAS J. KASPARI.
